UNITED STATES PATENT OFFICE.

HARRY W. MACDOUGALL, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed December 19, 1921. Serial No. 523,234.

To all whom it may concern:

Be it known that I, HARRY W. MACDOUGALL, a citizen of the United States, residing at East Orange, in the county of Essex, State of New Jersey, have invented certain new and useful Improvements in Telephone Systems, of which the following is a full, clear, concise, and exact description.

This invention relates to telephone systems and more particularly to such systems in which the signals for a plurality of trunk lines extending between widely separated stations are controlled over a single signaling path common to such trunk lines.

In systems of this character repeater equipments may be included in the trunk line at intermediate stations, and in order to economize on these equipments it is desirable that the filament circuits of the vacuum tubes employed therein shall be completed only when the trunk line, of which they are a part, is in use.

The present invention is a continuation in part of my application filed December 23, 1919, and bearing Serial No. 346,900.

It is the object of this invention to provide improved means for and methods of associating the common signaling path with the particular trunk line taken for use, for controlling the filament circuits of the repeater equipments in this trunk line and for operating signals associated with the selected trunk line over the common signaling path.

The means provided by the present invention for attaining this object will be more readily understood by reference to the accompanying drawings in which Figs. 1 to 3, when arranged with Fig. 2 to the right of Fig. 1 and Fig. 3 to the right of Fig. 2, are a diagrammatic representation of a telephone system embodying the present invention. Fig. 1 shows the equipment located at an office X. Fig. 2 shows that at an intermediate repeater station Y and Fig. 3 shows that at an office Z. Although but one repeater station Y is shown, it will be apparent from the subsequent description that any number of such stations might be employed. A single trunk line L¹ terminating in jacks 10 and 110 at offices X and Z respectively and in multiple jacks is shown, but in practice many such lines would be associated with a single signaling path com-

mon to a group of lines. Only the ends of 55 cord circuits A and B which cooperate with the trunk lines L are shown, as their other ends may be of any design suitable for operating with subscribers' or local trunk lines terminating in the offices X and Z. 60

In order that signals may be sent in either direction, duplicate apparatus is provided, that located at office X and employed in establishing connections from office X to office Z being designated by numerals under 100, each corresponding piece of apparatus at office Z or employed in signaling therefrom to office X being numbered one hundred more than the piece to which it corresponds, for example, jack 110 at office Z corresponds to 70 jack 10 at office X. As these corresponding parts are identical in structure and function, but one set will be described.

In the lower left hand dotted rectangle in Fig. 1 is shown a selector switch 30, having an arm 33 driven by a self-interrupting magnet 34 over contacts individual to the various trunk lines of the group. In the right hand dotted rectangle is shown a selector switch 40 having arms 42 and 43 which are moved simultaneously by motor magnet 47 over their associated contacts also equal in number to the lines in a group. A selector switch 50 having an arm 54 rotated over its contacts by motor magnet 53 is 85 shown below the dotted rectangles. To allow simultaneous signaling in both directions there is provided the usual duplex equipment comprising differentially wound polarized relays 28 and 29, metallic conductor 80, and balanced artificial line AL. As the specific telephone repeater circuits form no part of the present invention they have been indicated by the dotted rectangle RI, only the ends of the filament circuits, terminating in contacts of relays 70 and 170, being shown. 90 95

It is believed that the invention will be readily understood from a consideration of the description of the operation of the system which is as follows:

Operator at office X initiates a call.

The operator at office X, desiring to communicate with the operator at office Z, inserts plug 1 of a link circuit A at office X into jack 10 of line L¹. Relays 2 and 11 thereupon operate over a circuit extending

from battery through the winding of relay 2, the sleeve contacts of plug 1 and jack 10, and the winding of relay 11 to ground. In closing its right-hand alternate contact, relay 11 operates busy signals 72 associated with the multiples of jack 10 of which one is shown, over a circuit extending from ground, the right-hand alternate contact of relay 11, the normal contacts of relays 13 and 14 to battery through the windings of the various signals 72. Relay 12 also operates over an obvious circuit closing the circuit for and starting the operation of motor magnet 34, such circuit extending from battery through the winding and contact of motor magnet 34, the normal contact of relay 31, and the right-hand alternate contact of relay 12 to ground. The operation of relay 12 also energizes relay 13, whereupon the ground for maintaining the signals 72 operated is transferred to the continuity contact of relay 13. Immediately upon inserting the plug 1 into the jack 10, the operator actuates ringing key 3, causing the operation of relay 23 over a circuit extending from the source of alternating current through the lower alternate contact of key 3, the ring contacts of plug 1 and jack 10, lower normal contact of relay 18, the condenser 24, the winding of relay 23, the upper normal contact of relay 18, the tip contacts of jack 10 and plug 1, and the upper alternate contact of key 3 to ground. Relay 22 thereupon operates over an obvious circuit and locks in an operated condition over a circuit extending from battery through the winding and upper alternate contact of relay 22 and the right-hand normal contact of relay 20 to ground. The closure of the inner alternate contacts of relay 22 short circuits the windings of the repeating coil to prevent the transmission of the ringing current therethrough while the closure of the lower alternate contact of relay 22 connects ground through the winding of relay 20 to the terminal individual to line L^1 , of selector switch 30.

In response to the operation of the motor magnet 34, the arm 33 travels over the bank of contacts of the selector switch 30, and when it engages the contact individual to the line L^1 , relays 31 and 20 operate over a circuit established from battery through the winding of relay 31, the arm 33 of the selector switch 30 and the contact engaged thereby, the winding of relay 20 and the lower alternate contact of relay 22 to ground. The opening of the normal contact of relay 31 disables the motor magnet 34 and permits the arm 33 to remain in engagement with the contact individual to the line L^1 . Relay 31 locks over a circuit extending from battery through the winding and the left-hand alternate contact of relay 31 and the contact of relay 45 to ground. The closure of the

right-hand alternate contact of relay 31 closes a circuit for the motor magnet 47 of the selector switch 40 which extends from battery through the winding and contact of motor magnet 47, the left-hand normal contact of relay 41, and the right-hand alternate contact of relay 31. The motor magnet 47 thereupon causes the synchronous rotation of arms 42 and 43 which are mounted upon the same shaft of the selector switch. 75

In operating, relay 20 closes its alternate contacts and opens its normal contacts, the closure of the left-hand alternate contact thereof connecting the positive terminal of battery to the interconnected terminals of the terminal bank associated with the arm 43. The closure of the middle alternate contact of relay 20 connects ground to the terminal individual to the line L^1 of the terminal bank associated with the arm 42. The opening of the right-hand normal contact and the closure of the right-hand alternate contact of relay 20 provide a substitute locking circuit for relay 22 which extends from battery through the winding and upper alternate contact of relay 22, the right-hand alternate contact of relay 20, the right-hand normal contact of relay 41, and the contact of relay 45 to ground. The arm 42 rotates until it engages the terminal individual to the line L^1 , whereupon relay 41 operates over a circuit extending from battery through the winding of relay 41, the arm 42 and the contact engaged thereby, and the middle alternate contact of relay 20 to ground. The opening of the left-hand normal contact of relay 41 disables the motor magnet 47 so that arm 42 remains in engagement with the terminal individual to the line L^1 . The opening of the right-hand normal contact of relay 41 releases relay 22, and the closure of the right-hand alternate contact of relay 41 operates relay 44 over a circuit extending from battery through the winding of relay 44, the right-hand alternate contact of relay 41, and the contact of relay 45 to ground. Relay 44 thereupon locks over a circuit extending from battery through the winding and left-hand contact of relay 44 and the contact of relay 45 to ground. The release of relay 22 releases relay 20. The release of relay 20 removes the ground from the terminal individual to the line L^1 of selector switch 40, so that relay 41 releases, thereby completing the operating circuit of motor magnet 47, so that arms 42 and 43 of the selector switch 40 continue in their rotation. Upon arm 42 engaging the last terminal of the bank, relays 45 and 41 operate over a circuit extending from battery through the winding of relay 41, the contact arm 42 and the terminal engaged thereby, the right-hand contact of relay 44, and the winding of relay 45 to ground. The operation of relay 45 releases relays 44 and 31 and the release of the 125 130

relay 44 in turn releases relays 41 and 45. The release of relay 31 again establishes the circuit for magnet 34 so that the selector switch 30 will continue to operate as long as plug 1 remains in jack 10, but will perform no function until one of its contacts is grounded either by the seizure of another trunk line or by the transmission of other signals over trunk L^1 by the operator at A.

10 Each time that the arm 43 engages a terminal of the associated bank prior to its engagement with the terminal corresponding to the line L^1 , an impulse of current of positive polarity is transmitted over the duplex equipment comprising relays 28 and 29, common signaling conductor 80 and the artificial lines indicated at AL. These impulses pass over a circuit extending from positive terminal of battery through the left-hand alternate contact of relay 20, the terminal engaging contact arm 43 of the selector 40, from thence over one path through the lower winding of relay 28 and the artificial line to ground and over another path through the upper winding of relay 28, the common signaling conductor 80, the upper winding of relay 29, the lower winding of said relay, and through the artificial line AL to ground. The direction of the current flowing through this circuit causes the relay 29 to close its lower contact but leaves relay 28 inert. In response to the first of such impulses relay 67 is operated over a circuit extending from battery through the contact and winding of motor magnet 68 associated with the selector switch 60, the right-hand winding of relay 67 and the lower contact of relay 29 to ground. Relay 67 thereupon locks over a circuit established from battery through the left-hand winding and left-hand contact of relay 67 and the contact of relay 64 to ground. Motor magnet 68 responding to each closure of the lower contact of relay 29 causes the synchronous rotation of arms 61 and 62 of the selector switch 60. Therefore, the arms 61 and 62 will be advanced corresponding to the number of impulses transmitted by the arm 43 of the selector switch 40, and upon the completion of the series they will rest upon terminals corresponding to the line L^1 . Thereupon slow relay 71 operates over a circuit extending from battery through the winding of relay 71, the terminal individual to the line L^1 of the bank associated with the arm 61, and the arm 61 to ground. Relay 70 thereupon operates over a circuit extending from battery through the winding of relay 70, the right-hand alternate contact of relay 71, and the left-hand normal contact of relay 66 to ground. Relay 70 in operating locks over a circuit extending from battery through the winding and middle contact of relay 70 and the left-hand normal contact of relay 66 to ground. The closure of the left-hand alternate contact of relay 70 completes the filament current supply circuit of the repeater R^1 which is associated with the line L^1 so that such repeater is adapted for operation in connection with conversations over the line. The repeater R^1 may be similar in all respects to the repeater shown in Fig. 3 of United States Patent No. 1,413,708, granted to John Davidson, Jr., April 25, 1922. The closure of the left-hand alternate contact of relay 71 causes the operation of relays 65 and 63 over a circuit extending from battery through the winding of relays 65 and 63 in series, the left-hand alternate contact of relay 71 and the contact of relay 64 to ground. Relays 65 and 63 are locked in a circuit from grounded battery through the winding of relay 65, the winding and right-hand alternate contact of relay 63 to ground at the contact of relay 64. The opening of the right-hand normal contact of relay 65 disconnects positive battery from the interconnected terminals of the bank associated with the arm 62 over a circuit extending from the positive terminal of the battery through the right-hand contact of relay 67 and the right-hand contact of relay 65. The closure of the right-hand alternate contact of relay 65 connects ground to the interconnected terminals associated with the arm 62. The closure of the left-hand alternate contact of relay 65 completes a circuit for motor mechanism 68 extending from battery through the contact and winding of motor mechanism 68, the left-hand alternate contact of relay 65, and the normal contact of relay 64 to ground. Thereupon the arms 61 and 62 continue in their rotation until they engage the last terminal of the associated banks. In passing from the contact associated with the line L^1 , arm 61 interrupts the circuit of relay 71, which opens its right-hand alternate contact to break the original energizing circuit for relay 70 which, however remains locked up to ground on the outer left hand armature and normal contact of relay 66. Relay 71 in closing its normal contact also completes a circuit from battery through the winding of relay 70, the normal contact of relay 71, and the right-hand alternate contact of relay 70 to ground. In engaging the last terminal of its associated bank, arm 61 completes an operating circuit for relay 64, which may be traced from battery through the left-hand alternate contact of relay 63, the winding of relay 64, the last terminal of the bank associated with the arm 61, and the arm 61 to ground. The motor mechanism 68 is thereupon disabled and relays 63, 65 and 67 are released, the release of relay 63 causing the release of relay 64.

Upon each engagement of the arm 62

with a terminal of the associated bank prior to its engagement with the contact corresponding to the line L^1 , an impulse of current of positive polarity is transmitted over the circuit extending from the positive terminal of the battery through the right-hand contact of relay 57, the right-hand normal contact of relay 65, the engaged terminal of the bank, the contact arm 62, the upper winding of relay 128, the common signaling conductor 180, the upper winding of relay 129, the lower winding of said relay, through the artificial line AL to ground. Each such impulse of current causes the relay 129 to close its contact completing a circuit for motor magnet 153 extending from battery through the contact and winding of motor magnet 153 and the contact of relay 129 to ground. In response to the operation of the motor magnet 153, the arm 154 advances. Upon the completion of the series being transmitted, the arm rests upon the terminal which is individual to the line L^1 , whereupon relay 119 operates over a circuit extending from battery through the winding of relay 119, the terminal individual to the line L^1 and the arm 154 to ground. In operating, relay 119 causes the operation of relay 118 over an obvious circuit which causes the operation of relay 117 over a circuit extending from the source of alternating current through the lower alternate contact of relay 118, the right-hand normal contact of relay 111, the right-hand winding of relay 117, and the upper alternate contact of relay 118 to ground. Lamp 116 is thereupon lighted over a circuit extending from battery through the contact of relay 117 to ground, and busy signals 172 individual to each multiple of jack 110 are operated over a circuit from battery through the windings of magnets 172, the normal contacts of relays 114 and 113, the left-hand normal contact of relay 111 and the contact of relay 117 to ground. Relay 117 is locked over a circuit extending from battery, through the middle normal contact of relay 111, the left-hand winding and contact of relay 117, to ground. Relay 151 operates over a circuit extending from battery, through the winding of relay 151, the middle alternate contact of relay 118, and the normal contact of relay 152 to ground and locks through its middle alternate contact. Motor magnet 153 thereupon begins operating over a circuit extending from battery, through the contact and winding of motor magnet 153, the left-hand alternate contact of relay 151 and the normal contact of relay 152 to ground. Arm 154 is thereby caused to continue in its rotation until it engages the last terminal of the associated bank, whereupon relay 152 operates over a circuit extending from battery, through the right-hand alternate contact of

relay 151, the winding of relay 152, the terminal of the bank engaged by arm 154, and the arm 154 to ground. Relay 151 thereupon releases, and in releasing causes the release of relay 152 and stops the operation 70 of motor magnet 153.

Operator at office Z answers the call.

Observing the lighted condition of lamp 116, the operator at office Z inserts plug 101 of link circuit B thereat into the jack 110 of line circuit L^1 . Relays 102 and 111 operate over a circuit extending from battery, through the winding of relay 102, the sleeve contacts of plug 101 and jack 110, and the winding of relay 111 to ground. The closure of the right-hand alternate contact of relay 111 causes the operation of relay 112 which in closing its right-hand alternate contact causes the operation of relay 113, and at its left-hand alternate contact completes a circuit for the motor magnet 134 of the selector switch 130. In response to the operation of magnet 134 the arm 133 is rotated over its contacts, but as relay 122 is inert, no circuit will be completed for relay 131 and no signal will be sent out at this time. The opening of the middle normal contact of relay 111 releases relay 117, thereby extinguishing lamp 116. However, the busy signals 172 are maintained in an operated condition over a circuit traceable from battery through the windings of magnets 172, the normal contacts of relay 114, and the continuity contacts of relay 113 to ground. The opening of the right-hand normal contact of relay 111 removes the right-hand operating winding of relay 117 from its bridged relation across the conductors of line circuit L^1 . By the actuation of the listening key 104 of the link circuit B, the operator at office Z is thereupon enabled to communicate with the operator at office X.

Operator at office X rings for lighting the supervisory signal at office Z.

In case the operator at office X desires to signal the operator at office Z after connection has been made with the line circuit L^1 at both offices, the operator at office X actuates the ringing key 3 of the line circuit A, thereby causing the operation of ringing response relay 23 as previously described to transmit a series of impulses through the selecting apparatus to the office Z in a manner similar to that described in connection with the initiation of the call. However, since the relay 117 is no longer operatively associated with the line circuit L^1 it does not operate, but the supervisory relay 106 in the link circuit B is operated over a circuit extending from the source of alternat-

ing current through the lower alternate contact of relay 118, ring contacts of jack 110 and plug 101, the lower normal contact of ringing key 103, the right-hand winding of relay 106, the condenser 107, the upper normal contact of key 103, the tip contacts of plug 101 and jack 110, and the upper alternate contact of relay 118 to ground. Lamp 105 is thereupon lighted over a circuit extending from battery, through the alternate contact of relay 102, the normal contact of listening key 104, the lower contact of relay 106, and the lamp 105 to ground. The operator at office Z, observing the lighted condition of the lamp 105, actuates listening key 104 so that she may communicate with the operator at office X. The actuation of the listening key 104 in addition to connecting the usual operator's telephone set (not shown) with the talking conductors of the line circuit also extinguishes lamp 105 and releases relay 106.

Operator at office X disconnects.

Upon the completion of the conversation, the operator at office X actuates ringing key 3 to transmit a disconnect signal to the operator at office Z in exactly the same manner as that described in connection with the reringing of the operator at office Z. The plug 1 may be removed from jack 10 as soon as key 3 has been actuated, whereupon relays 2, 11 and 12 release. Relay 13 also releases due to the release of relay 12 and as such relay is slow in releasing, relay 14 operates over a circuit extending from battery, through the winding of relay 14, the left-hand contact of relay 13, and the normal contact of relay 12 to ground. Relay 14, thereupon, locks in an operated condition over the circuit extending from battery, through the winding and an alternate contact of relay 14, and the right-hand normal contact of relay 21 to ground. The closure of contact 73 of relay 14 provides a substitute circuit to maintain the busy signals 72 operated until the apparatus is completely restored, after the release of relay 11 opens their original circuit. The closure of the outer right-hand alternate contact of relay 14 connects ground from the normal contact of relay 22, through the right-hand alternate contact of relay 14 and the winding of relay 21 to a terminal of the selector switch 30 individual to the line L¹. The closure of the left-hand alternate contact of relay 14 closes the operating circuit for motor magnet 34 and the arm 33 is thereby rotated until it engages the terminal individual to the line L¹. Relays 21 and 31 thereupon operate over the circuit extending from battery, through the winding of relay 31, the arm 33 and the terminal engaged thereby, the winding of relay 21, the outer right-hand

alternate contact of relay 14 and the normal contact of relay 22 to ground. The opening of the left-hand normal contact of relay 31 disables the motor magnet 34 so that arm 33 remains in engagement with the terminal individual to the line L¹. Relay 31 locks over the circuit extending from battery, through the winding and left-hand alternate contact of relay 31, and the contact of relay 45 to ground. The closure of the right-hand alternate contact of relay 31 closes a circuit for the motor magnet 47 from battery, through the winding and contact of motor magnet 47, the left-hand normal contact of relay 41 and the right-hand alternate contact of relay 31 to ground. In response to the operation of motor magnet 47, arms 42 and 43 rotate synchronously. The closure of the middle alternate contact of relay 21 connects ground to the terminal individual to the line L¹ of the bank of terminals associated with arm 42. The closure of the left-hand alternate contact of relay 21 connects the negative terminal of the battery to the interconnected terminals of the bank associated with the arm 43. When the arm 42 reaches the terminal individual to the line L¹, relay 41 operates over a circuit extending from battery, through the winding of relay 41, the arm 42 and the terminal engaged thereby, and the middle alternate contact of relay 21 to ground. The opening of the left-hand normal contact of relay 41 disables motor magnet 47 so that arm 42 is maintained in engagement with the terminal individual to the line L¹. The closure of the alternate contact of relay 41 causes the operation of relay 44 over a circuit extending from battery, through the winding of relay 44, the alternate contact of relay 41 and the normal contact of relay 45 to ground. Relay 44 thereupon locks over a circuit completed from battery, through the winding and left-hand contact of relay 44, and the contact of relay 45 to ground. Upon each engagement of the arm 43 with a terminal of the associated bank prior to the engagement of the arm 42 with the terminal individual to the line L¹, a circuit is completed from the negative terminal of battery, through the left-hand alternate contact of relay 21, the terminal of the bank associated with the arm 43, the arm 43, the upper winding of relay 28, the common signaling conductor 80, through the windings of relay 29, and the artificial line AL to ground. In response thereto, relay 29 closes its upper contact causing the operation of relay 66 and motor magnet 68 over a circuit extending from battery, through the contact and winding of motor magnet 68, the right-hand winding of relay 66, and the upper contact of relay 29 to ground. In operating, upon response to the first of such impulses, relay 66 locks over a circuit extending from bat-

ter, through the left-hand winding and left-hand alternate contact to relay 66 and the contact of relay 64 to ground. The motor magnet 68 causes the arms 61 and 62 to rotate synchronously until the terminal individual to the line L^1 is engaged by the arm 61 whereupon relay 71 is operated over a circuit extending from battery, through the winding of relay 71, the terminal individual to the line L^1 and the arm 61 to ground. Due to the operation of relay 71 and inasmuch as relay 66 is at this time operated and locked to remove ground from its normal contact, relay 70 is released to disable the battery supply circuit for the filament for the repeater R^1 restoring such repeater to normal. As in the previous case where the originating signal is transmitted from office X to office Z, the relays 63 and 65 operate over the circuit extending from battery, through the windings of relays 65 and 63 in series, the left-hand alternate contact of relay 71, and the contact of relay 64 to ground. Relays 63 and 65 lock over a circuit extending from battery, through the winding of relay 65 and the winding of relay 63 in series, the right-hand alternate contact of relay 63 and the contact of relay 64 to ground. Motor magnet 68 thereupon commences to operate and cause the advancement of arms 61 and 62. The advancement of arm 61 opens the circuit for relay 71 which thereupon releases. When arm 61 reaches the last terminal of the associated bank, relay 64 is operated over a circuit extending from battery, through the left-hand alternate contact of relay 63, the winding of relay 64, the terminal engaging arm 61 to ground. In operating, relay 64 causes the release of relays 63, 65 and 66 and opens the circuit of motor magnet 68 so that the arms 61 and 62 cease in their rotation. Although, each time the arm 62 engages a terminal of the associated bank prior to reaching the terminal corresponding to the line L^1 , an impulse of current of negative polarity is transmitted over the circuit extending from negative terminal of battery, through the right-hand alternate contact of relay 66, the normal contact of relay 65, the terminal engaged by the arm 62, the arm 62, the upper winding of relay 128, the common signaling conductor 180, both windings of relay 129 and the artificial line AL to ground, the polarity of such current produces no effect upon the circuit since relay 129 is adapted to close a contact in response to the opposite polarity only. If more than one repeater station were used, however, these impulses would cause relay 29 of the next repeater station to close its upper contact to open the filament circuit at its station.

When the operator at office Z removes the plug 101 of the link circuit B from the jack

110, all apparatus of the system is returned to its normal condition and is prepared for the initiation of another call.

Although the operation of the system has been described in connection with a call originating at office X and received at office Z, it is evident from the duplication of the apparatus at the offices X, Y and Z that the calls may be originated at office Z and transmitted to office X through any desired number of repeater stations in a similar manner, the corresponding elements operating as described in connection with the signals which were described in the previous outline. It will be noted that the relays 70 and 170 control the repeater equipment filament circuit and the need for the duplicate arrangement, one of which responds to signals being received in one direction while the other responds to signals received from the opposite direction, is evident when it is considered that the signals may be sent in both directions at the same time for selecting or restoring the repeater equipment.

What is claimed is:

1. In a telephone system the combination with a plurality of trunk lines and a signaling path common thereto extending between two stations, of a selective switch individual to said signaling path and means responsive to the taking for use of any one of the trunk lines and to the impression of current on said line for operating said selective switch to send over said common signaling path a series of impulses corresponding in number to the line taken for use.

2. In a telephone system the combination with a plurality of trunk lines and a signaling path common thereto extending between two stations, of a number of cord circuits for association with said trunk lines, a selective switch individual to said signaling path, means responsive to the association of one of said cord circuits with any one of said trunk lines and to the impression of a distinctive current on said trunk line for operating said selective switch to send over said common signaling path consecutive impulses of one polarity, and means responsive to the dissociation of said cord circuit from said line for operating said selective switch to send over said common signaling path a series of impulses of opposite polarity.

3. In a telephone system the combination with a plurality of trunk lines and a signaling path common thereto extending between terminal stations, of normally inoperative repeater equipment included in said trunk lines at intermediate stations, a number of cord circuits for association with said trunk lines at said terminal stations, a selective switch individual to said signaling path at each of said stations, means responsive to the association of one of said cord circuits

with any one of said trunk lines and to the impression of a distinctive current on said trunk line for operating one of said selective switches to send over said common signaling path a series of impulses of which the number is controlled by the trunk line taken for use, means responsive to said impulses for operating the selective switch at said intermediate station, and means responsive to such operation of said switch to render operative the repeater equipment included in the trunk line with which said cord circuit has been associated.

4. In a telephone system the combination with a plurality of trunk lines and a signaling path common thereto extending between terminal stations, of normally inoperative repeater equipment included in said trunk lines at intermediate stations, a number of cord circuits for association with said trunk lines at said terminal stations, a selective switch individual to said signaling path at each of said stations, means responsive to the association of any one of said cord circuits with any one of said trunk lines, and to the impression of a distinctive current on said trunk line for operating one of said selective switches to send over said common signaling path a series of impulses of one polarity, means operated in response to the dissociation of said associated cord circuit from said trunk line for operating said selective switch to send over said signaling path a series of impulses of opposite polarity, means responsive to said first series of impulses for rendering operative the repeater equipment included in the trunk line with which said cord circuit has been associated, and means responsive to said second series of impulses for rendering said repeater equipment inoperative.

5. In a telephone system the combination with a plurality of trunk lines and a signaling path common thereto extending between terminal stations, of signals at said stations, a number of cord circuits for association with said trunk lines, selective switches having contacts individual to said trunk lines at each of said stations, means responsive to the association of any one of said cord circuits with any one of said trunk lines and to the impression of a distinctive current on said trunk line for operating one of said selective switches to send over said common signaling path a series of impulses of which the number is controlled by the trunk line taken for use, means responsive to said impulses for operating another of said selective switches to select a contact individual to the calling line, and means responsive to such selection for operating a signal individual to said line.

6. In a telephone system the combination with a plurality of trunk lines and a signaling path common thereto extending be-

tween terminal stations, a number of cord circuits for association with said trunk lines, signals individual to said trunk lines, signals individual to said cord circuits, selective switches having contacts individual to said trunk lines at each of said stations, means responsive to the association of any one of said cord circuits with any one of said trunk lines and to the impression of a distinctive current on said trunk line for operating one of said selective switches to send over said common signaling path a series of impulses of which the number is controlled by the trunk line taken for use, means responsive to said impulses for operating another of said selective switches to select a contact individual to the calling line, and means responsive to such selection for operating a signal individual to said line, said selective switches being responsive to the impression of a distinctive current on one end of said line after the association of a cord circuit with the other end of said line to operate a signal individual to said cord circuit.

7. In a telephone system the combination with a plurality of trunk lines and a signaling path common thereto extending between terminal stations of normally inoperative repeater equipment included in said trunk lines at intermediate stations, signals associated with each trunk line at said terminal stations, means including a selective switch at each terminal station for controlling said signals, means including a selective switch at each intermediate station for controlling the repeater equipment thereat, and means responsive to the initiation of a call on any one of said trunk lines and to the impression of a distinctive current on said trunk line for operating one of said selective switches at each station simultaneously.

8. In a telephone system the combination with a plurality of trunk lines and a signaling path common thereto extending between two stations, of a selective switch, and means operable when any one of said trunk lines is taken for use for operating said switch to send over said common signaling path a series of impulses corresponding in number to the line taken for use.

9. In a telephone system the combination with a plurality of trunk lines and a signaling path common thereto extending between two stations, of a number of cord circuits for association with said trunk lines, signals at one station each individual to one of said trunk lines, a selective switch individual to said signaling path, means responsive to the association of one of said cord circuits with any one of said trunk lines at one station and the impression of a distinctive current on said trunk line for operating said switch to send over said common signaling path a series of impulses of one polarity to operate the signal at the

first named station individual to said trunk line, and means responsive to the disconnection of said cord circuit from said line for operating said switch to send over said common signaling path a series of impulses of opposite polarity.

10. A source of impulses, a repeater including a step-by-step switch for repeating impulses received thereby, signaling devices, means including a switch controlled by repeated impulses received thereby for effecting the operation of a signaling device corresponding to the number of impulses received and after said impulses have ceased 15 and means for maintaining this signaling device operated independently of said second mentioned switch.

11. In a signaling system, a plurality of transmission circuits interconnecting two stations, a normally inactive repeating arrangement included in each of the transmission circuits, a signaling path common to the transmission circuits and interconnecting the stations, means controlled by 25 the selection of one of the transmission circuits at either station to transmit a signal over the signaling path, and means responsive to the transmission of the signal to render active the repeating arrangement included in the selected transmission circuit.

12. A signaling system comprising a pair of stations, a plurality of transmission circuits interconnecting the stations, a repeater included in each transmission circuit, a common signaling path interconnecting the stations, and means at each station for controlling the repeater of any transmission circuit over the common signaling path.

13. In a telephone system, a telephone line, sources of impulses of different characteristics, and means including a repeater comprising a step by step switch for associating one of said sources of impulses with said line upon the seizure thereof and

another of said sources therewith, upon its release.

14. In a telephone system, a plurality of lines, a cord circuit, a key associated therewith, an automatic switch common to said lines, means responsive to the actuation of 50 said key subsequent to the association of said cord with one of said lines for conditioning said switch to function with the seized line, a signal associated with said line, a source of impulses, a repeater therefor comprising a step by step switch, a signal path, and means responsive to the association 55 of said automatic switch with said line for connecting the source of impulses to said repeater to transmit a set of impulses individual to said line over said signal path to effect the actuation of said signal.

15. The method of signaling which comprises translating alternating signaling current into a code of direct current impulses, 60 translating the direct current impulses into a step by step movement, translating the step by step movement into a code of direct current impulses, and translating the last 65 said code of impulses into a steady signal indication.

16. In a signaling system, a combination of means for producing different codes of current impulses, a repeater therefor comprising a step by step switch actuated in a 75 particular manner for each code of impulses, signaling devices, and means including a switch controlled by each setting of the first mentioned switch in response to a particular code of impulses to cause the operation of 80 the corresponding signaling device and means for continuing the operation of said signaling device independently of the means for operating it.

In witness whereof, I hereunto subscribe 85 my name this 14th day of December A. D., 1921.

HARRY W. MacDOUGALL.
